UNITED STATES PATENT OFFICE.

GEORGE S. STUART, OF BRADFORD, PENNSYLVANIA.

ADJUSTABLE-SEAT ATTACHMENT.

1,356,235.

Specification of Letters Patent. Patented Oct. 19, 1920.

Application filed January 10, 1920. Serial No. 350,603.

To all whom it may concern:

Be it known that I, GEORGE S. STUART, a citizen of the United States, residing at Bradford, in the county of McKean and 5 State of Pennsylvania, have invented certain new and useful Improvements in Adjustable-Seat Attachments; and I do hereby declare the following to be a full, clear, and exact description of the invention, such 10 as will enable others skilled in the art to which it appertains to make and use the same.

My present invention relates to adjustable seat attachments for use as attached to 15 or in connection with bath tubs, or other household appliances, such as beds, or other articles of furniture, and is also adapted to be attached to walls, shelves, or tables where it is desired to provide a folding or an 20 adjustable seat or shelf which may be conveniently put into use or put out of the way as may be desired.

My present invention relates more especially to a modification of the apparatus described and claimed in my Patent No. 25 1,325,423, granted December 16, 1919 and entitled improvements in folding seat attachments.

My invention will be more fully understood after reference to the accompanying drawings, in which like parts are indicated by similar reference symbols throughout the several views, and in which:—

Figure 1 shows the device as applied to a 30 metallic bath tub, the tub being shown in section.

Fig. 2 is a view of the device shown in Fig. 1 as seen from the right of said figure, parts being broken away.

Fig. 3 shows a section along the line 3—3 of Fig. 1, but shows the front door of the cabinet open and the shelf folded on top of the cabinet.

Fig. 4 is a perspective view showing the 45 spring catch used for securing the folding shelf to the edge of the metallic bath tub.

Fig. 5 is a sectional view of a modification in which two pairs of adjustable legs are substituted for the cabinet shown in 50 Figs. 1 to 3.

Fig. 6 shows another modification in which a single pair of legs only are used; and

Fig. 7 shows still another modification in 55 which a single pair of legs is used, but these fold up into the body of the seat.

Referring first to Figs. 1 to 4, A represents a shelf hinged as at α to the cabinet B, and having a shoulder α' abutting against the face of said cabinet, and a 60 groove α'' adapted to fit snugly over the rounded edge α of a metallic bath tub X of the usual construction.

If desired this shelf A may be rigidly attached to the cabinet B, but I prefer it 65 hinged thereto as shown.

B represents the cabinet which is divided by the partition b into a receptacle B' for towels or the like, and by the partial partition b' into a receptacle for shoe brushes, 70 whisk brooms, or other articles, not shown.

The cabinet is mounted upon legs C having extension members C' adjustably connected to the leg C by the bolts D and butterfly nuts d. Thus the cabinet or each leg 75 thereof may be raised or lowered to conform to the height of the bath tub, inequalities in the floor, or the like.

The side walls of the cabinet may be provided with suitable hand holes b'' , and access 80 to the chamber B' may be had by means of a suitable door F controlled by a latch f, as shown in Fig. 1. The front of the cabinet is provided with an opening which may be closed by the swinging door G, secured to the blocks H pivoted on the rod I. This door G is provided with a suitable latch g. When the said door G is swung to the open position shown in Figure 3, it 85 may be used as a foot rest for use in polishing shoes, or the like. These blocks H are secured near their front ends, as at h, to the door G, and at their rear ends have arms h' adapted to engage beneath the bottom of the cabinet, as shown in Fig. 3. 90

It will be obvious that the device may be applied to the side of a bath tub, as shown in Fig. 1, or the shelf may be folded over and the device used as a table or stand, as 95 shown in Fig. 3.

In the modification shown in Fig. 5 instead of the cabinet having chambers therein, I provide a shelf M grooved as at m to fit over the rim α of the tub X, and this shelf is supported on four legs N having 100 adjustable extensions N' which may be raised or lowered by means of the bolts D and butterfly nuts d, as hereinbefore described.

In the modification shown in Fig. 6 a single pair of legs N² only is used to support the shelf or seat M'; and in the modification

shown in Fig. 7 the legs N^3 supporting the shelf M^2 are pivoted to the rod I' and swing up into the body of the seat as indicated in dotted lines in said figure.

5 In the arrangement shown in Fig. 7 I have provided a rail Z carried by suitable brackets Z' to which the free end of the seat is attached.

In applying the device to the edge of a 10 bath tub, rail, or other article, the spring catch A^o is swung out of the way, permitting the groove a^2 of the seat to engage the article to which the seat is to be attached, and then upon releasing the seat the spring 15 will snap into engagement and hold the device in place.

It will be obvious that the device may be used also in connection with the rails of 20 beds, or other similar article, as illustrated and described in my patent aforesaid.

It will be obvious that various modifications might be made in the herein described 25 apparatus and in the construction, combination and arrangement of parts which can be used without departing from the spirit of my invention; and I do not mean to limit the invention to such details of construction except as particularly pointed out in the 30 claims.

Having thus described my invention what I claim and desire to secure by Letters 35 Patent of the United States is:—

1. A removable seat, for use with bath tubs or like household articles having a flanged edge curved to form an arch, having notched supporting rails for said seat

adapted to fit over said arch, and a curved leaf spring secured to one of said supporting rails adjacent to its notch and adapted to snap into said notch when released, and 40 a vertically adjustable support for the opposite end of said seat, comprising a cabinet connected to said seat, and provided with a door, side blocks pivoted to said cabinet and secured to the lower edge of said door 45 and serving as stops for said door when swung to the lowered position, whereby said door may be used as a foot rest, and vertically adjustable legs for said cabinet, substantially as described. 50

2. A removable seat, for use with bath tubs or like household articles, having notched supporting rails adapted to engage said article, and a vertically adjustable support for the opposite end of said seat, comprising a cabinet connected to said seat, and vertically adjustable legs for said cabinet, substantially as described. 55

3. A removable seat, for use with bath tubs or like household articles, having notched supporting rails adapted to engage said article, and a vertically adjustable support for the opposite end of said seat, comprising a cabinet connected to said seat, and provided with a door, side blocks pivoted to 60 said cabinet and secured to the lower edge of said door and serving as stops for said door when swung to the lowered position, whereby said door may be used as a foot rest, and vertically adjustable legs for said cabinet, substantially as described. 65

GEORGE S. STUART.
